UNITED STATES PATENT OFFICE.

LOUIS W. RICE, OF NEW YORK, N. Y., ASSIGNOR TO BERNARD RICE'S SONS, INC., OF NEW YORK, N. Y., A CORPORATION OF NEW YORK.

DESIGN FOR A BOTTLE OR SIMILAR ARTICLE.

Application filed May 18, 1928. Serial No. 26,751. Term of patent 7 years.

To all whom it may concern:

Be it known that I, LOUIS W. RICE, a citizen of the United States, residing at 325 Fifth Avenue, New York city, in the county of New York and State of New York, have invented a new, original, and ornamental Design for a Bottle or Similar Article, of which the following is a specification, reference being had to the accompanying drawing, forming part thereof.

Fig. 1 is a side elevation showing the top of the bottle in broken lines; and

Fig. 2 is a top plan view.

I claim:

The ornamental design for a bottle or similar article, as shown.

LOUIS W. RICE.
